CLAIM

The ornamental design for a display screen or portion thereof with graphical user interface, as shown and described.

DESCRIPTION

The FIGURE is a front view of a display screen or portion thereof with graphical user interface showing our new design. The broken line showing of the display screen does not form part of the claimed design.

The stylistic “f” mark in the FIGURE is a trademark that is the property of Facebook, Inc. The “oheo” mark in the FIGURE is a trademark that is the property of Net Power and Light, Inc. Trademarks are the property of their respective owners.
